counselors.

UNITED STATES PATENT OFFICE.

DAVID J. NYSEWANDER, OF OWOSSO, MICHIGAN.

PUMP.

SPECIFICATION forming part of Letters Patent No. 359,516, dated March 15, 1887.

Application filed September 13, 1886. Serial No. 213,444. (No model.)

To all whom it may concern:

Be it known that I, DAVID J. NYSEWANDER, a citizen of the United States, and a resident of Owosso, in the county of Shiawassee and State 5 of Michigan, have invented certain new and useful Improvements in Pumps; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved 15 pump. Fig. 2 is a vertical sectional view of the same. Fig. 3 is a similar view taken at right angles to the former view. Fig. 4 is an inside view of one of the halves of the casing or base, and Fig. 5 is a sectional detail view 20 showing the fulcrum-bracket applied to a force-pump.

Similar letters of reference indicate corresponding parts in all the figures.

My invention has relation to hand-pumps; 25 and it consists in the improved construction and combination of parts of a casing for a pump, as hereinafter more fully described and claimed.

In the accompanying drawings, the letter A 30 indicates the cylinder of the pump, which is provided with the suction-pipe B at its lower end and with the delivery-pipe C at its upper end, and this delivery-pipe extends into the lower spherical portion, D, of a reservoir, E, at the upper end, the spherical portion having a delivery-spout, F, projecting from one side. The lower end of the spherical portion is formed with a neck, G, into which the delivery-pipe is inserted, and two 35 flanges, H H, having semicircular notches I in their meeting-edges, project from the inner sides of the halves J J of the casing or base for the pump. This casing incloses the upper portion of the delivery-pipe, and is formed 40 with a flaring lower portion, K, with which it rests upon the cover L of the well, and the upper ends of the halves are formed with segmental concave edges M, which bear against the lower portion of the spherical portion of 45 the reservoir, supporting the same. The

notched flanges at the upper ends of the halves fit with the notches between the spherical portion of the reservoir and the flange N at the lower end of the neck, and similar flanges, O O, having notches P, project from the inner 55 sides of the lower portions of the halves of the casing, clamping around the discharge-pipe.

Bolts Q, having nuts R, pass through perforations S in the halves of the casing, drawing them together, and the sides of the halves of 60 the casing are preferably formed with apertures T, formed by lattice-work, for the purpose of allowing fresh air to pass down into the well.

The upper end of the reservoir is formed 65 with an inwardly-beveled upper end, U, and a downwardly-projecting flange, V, projects from the edge of a cap, W, and fits around this inwardly-beveled end, having beveled or inclined lips or projections X upon its inner side, 70 which correspond in their incline to the incline or bevel of the end, and a set-screw, Y, passes through the flange at the opposite side to the projections and bears against the beveled end of the reservoir, binding the cap upon 75 the same.

The cap is provided with an aperture, Z, through which the piston-rod A' passes, either freely, as shown in the first four figures, or passing through a packing-box, B', as shown 80 in Fig. 5, and the fulcrum-bracket C' for the handle D' projects upward from the cap at the side diametrically opposite to the beveled projection upon the inner side of the flange.

It will be seen that by loosening the nuts 85 upon the bolts connecting the halves of the casing or base the spout may be turned to any side, as desired, and by loosening the binding-screw in the cap the cap may be turned so as to bring the handle in any desired position 90 with reference to the spout.

Having thus described my invention, I claim and desire to secure by Letters Patent of the United States—

In combination with a reservoir at the upper 95 end of the discharge-pipe of a pump, formed with a rounded lower portion having the discharge-spout, two halves of a casing or base formed with a flaring lower portion and with inwardly-projecting lips having semicircular 100

notches near the upper and lower ends, fitting, respectively, in a flanged neck upon the round portion of the reservoir and around the discharge pipe, and formed with concave segmental upper edges fitting upon the rounded portion of the reservoir, and nutted bolts drawing the two halves together, as and for the purpose shown and set forth.

In testimony that I claim the foregoing as my own I have hereunto affixed my signature to in presence of two witnesses.

DAVID J. NYSEWANDER.
